(Continued)

Primary Examiner — Kelley Donnelly(74) *Attorney, Agent, or Firm* — Raymond Sun(57) **CLAIM**

The ornamental design for a storage rack, as shown and described.

DESCRIPTION

FIG. 1 is a perspective view a storage rack showing my new design according to a first embodiment thereof.

FIG. 2 is a perspective view a storage rack showing my new design according to a second embodiment thereof; and,
FIG. 3 is a perspective view a storage rack showing my new design according to a third embodiment thereof.**1 Claim, 3 Drawing Sheets**| (56)	References Cited
